LIQUID SPRAYING APPARATUS

Benjamin L. Glattke, Toledo, Ohio

Application August 29, 1932, Serial No. 630,813

2 Claims. (Cl. 299—58)

The invention relates to spraying devices, but more particularly to devices of the character used in stores for creating a fine mist, or fog over vegetables to keep them fresh, and militate 5 against decay and spoilage, and an object is to produce an apparatus of this character having the new and improved features of construction, arrangement and operation hereinafter described.

10 Another object is to produce a spraying apparatus of the above type having an adjustable head for controlling the amount of fog or mist and for directing the fog in any desired direction.

The invention is shown by way of illustration, 15 in the accompanying drawing, in which:

Figure 1 is a vertical sectional elevation of the apparatus showing in dotted lines the head in tilted position;

Figure 2 is an enlarged transverse sectional view of the line 2—2 of Figure 1;

Figure 3 is an enlarged vertical sectional view showing the nozzle and removable tip mounted on the upper end of the inner tube;

Figure 4 is a plan view of a tip cleaner;

Figure 5 is an alternate form of head in which half the side walls are imperforate and an inclined spray-directing surface is provided on the top wall; and

Figure 6 is a vertical sectional view of an alternate form of spray-directing member.

The illustrated embodiment of the invention comprises an upright inner tube 10, the lower end of which is in screw threaded engagement with a mounting 11, which has a lateral inlet 12 to receive water under pressure. It is to be noted that the inlet opening is smaller than the diameter of the tube 10. The mounting 11 may be a permanent installation, and is connected by suitable pipes to the water supply. From the mounting 11 depends an extension 13 to which piping is connected to drain from the apparatus unused or surplus liquid. As shown, the extension 13 communicates with the inside of the mounting 11, and liquid is free to flow therethrough around 35 the liquid inlet passage 12.

Enclosing the inner tube 10 is an outer tube 11^a, which is supported by and in screw threaded engagement with the upper end portion 14 of the mounting 11 at its lower end, the upper end of 40 the tube 11^a extending beyond the end of the inner tube 10. A cup 15 having an enlarged upper portion 16 is mounted on the outer end of 45 the tube 11^a. The inner wall of the enlarged portion 16 is screw threaded to receive an adjustable head 17.

The head 17 consists of a ring 18 having external screw threads and a baffle plate 19 spaced outwardly from the ring 18, and is secured thereto by a plurality of pins 20. The underside of the plate 19 is slightly concave, and disposed centrally thereof is a polished surface 21, which in this instance is disc-shaped, and in the center is a pointed pin or projection 22. The region 23 outside of the smooth or polished disc 21 is rough or unpolished.

Mounted on the outer end of the inner tube 10, which, as shown in Figure 1, terminates short of the cup 15, is a nozzle 24 having a restricted outlet 25, into which is screwed a tip 26 having a fine port 27 through which liquid is discharged

in a fine needle-like stream. The liquid is discharged from the tip 26 at considerable pressure and impinges against the point 22 and surface 21, where it is deflected laterally into a fine mist or fog. The liquid will not adhere to any extent to the unpolished surface 23, and consequently some will drop into the cup 15 and flow down the pipe 11 to a collar 28, which is part of the nozzle 24, and is provided with a plurality of ports 29 through which the surplus liquid passes into the mounting 11.

It will be noted that the head 17 is longitudinally adjustable so that the baffle plate may be moved closer to or farther away from the cup 15 for increasing or diminishing the mist or fog. Under some conditions it is desirable to direct the fog or mist in a certain direction. This may be accomplished with the head 17 by unscrewing it from the cup 15, and resting in the cup in tilted position, as shown by the dotted lines in Figure 1. Obviously, the head may be tilted in any desired direction so that the spray will be deflected to the place or places desired.

As above mentioned, the tip 26 is removable so that other tips may be substituted having larger or finer ports 27. This enables the stream discharged from the inner tube 10 to be regulated as desired. Owing to the fineness of the port 27 it is sometimes necessary to clean out this port and for this purpose a cleaner 30 may be used. The cleaner 30 comprises a relatively small tube through which a wire 31 extends and projects beyond opposite ends of the tube. The intermediate portion of the tube is looped one or more times, as indicated at 32, to provide a handle and storage supply for the cleaner, and also retain the wire from slipping easily in the tube. By forcing one end or the other of the wire 31 through the port 27 it will be readily seen that cleaning may be conveniently accomplished.

55

As shown on Fig. 5, the head 17^a is provided with an imperforate side wall 18^a, which extends approximately half way around the head leaving an opening 19^a for the discharge of spray. 5 As shown, the side walls are screw-threaded for adjustment in the cup 15^a similar to the form above described. Instead of using the point 22 above mentioned, an inclined spray-directing surface 20^a may be provided, the inclination being such as to deflect the spray laterally through the discharge opening 19^a.

Figure 6 shows an alternate form of nozzle head and comprises a body portion 24^b in screw threaded engagement with the upper end of the liquid discharge pipe 25^b. The body portion is provided with a peripheral flange 26^b for engagement with the mounting tube 27^b. Formed in the flange are a series of notches 28^b through which the overflow may pass, corresponding in purpose to the ports 29 above described. Extending outwardly from the central portion of the body portion is a nozzle 29^b having a relatively small opening 30^b. In this instance the nozzle is integral with the head.

25 It is to be understood that numerous changes in details of construction, arrangement and operation may be effected without departing from the spirit of the invention, especially as defined in the appended claims.

30. What is claimed is:

1. A vaporizing apparatus comprising a tubu-

lar member, means for creating a fine stream of liquid longitudinally of said tubular member, a tubular member enclosing said first tubular member and having an enlarged outer end portion, baffle means on said enlarged outer end adapted to receive said stream, and an adjustable connection between said baffle member and the outer end of said second tubular member to enable said baffle member to be moved toward or away from said second tubular member, said baffle means being bodily removable from said second tubular member and adapted to be tilted for directing the spray in one direction or another as desired. 10

2. A vaporizing apparatus comprising a tubular member having an enlarged end portion, a head adjustably connected for longitudinal movement on said enlarged end portion, a spray-directing surface on said head and spaced outwardly therefrom, said head being bodily removable from and adapted to be tilted in said enlarged end portion for directing the spray in any desired direction, the said spray-directing surface having a centrally disposed polished surface against which a stream of liquid is adapted to be impinged and a pointed member within said polished surface, a substantially roughened surface surrounding said polished surface, and means within said tubular member for directing a relatively fine stream of liquid against said spray directing element. 15 20 25
